UNITED STATES PATENT OFFICE.

GEORGE M. LITTLE, OF PITTSBURGH, PENNSYLVANIA, ASSIGNOR TO WESTINGHOUSE ELECTRIC AND MANUFACTURING COMPANY, A CORPORATION OF PENNSYLVANIA.

POST-TYPE ARC-LAMP.

1,264,406.

Specification of Letters Patent. Patented Apr. 30, 1918.

Application filed December 4, 1913. Serial No. 804,655.

To all whom it may concern:

Be it known that I, GEORGE M. LITTLE, a citizen of the United States, and a resident of Pittsburgh, in the county of Allegheny and State of Pennsylvania, have invented 5 a new and useful Improvement in Post-Type Arc-Lamps, of which the following is a specification.

My invention relates to arc lamps, and it 10 has special reference to supporting structures for arc lamps.

My invention refers particularly to arc lamps which are adapted to be mounted upon posts or pedestals, and it has for its 15 object to provide supporting structures therefor that will permit inspections of the lamps and the necessary replacements to be readily made, and will allow of a weather proof design.

20 At present, it is usual to support an arc lamp upon a post or pedestal by suspending the lamp between the arms of a bifurcated or forked member which results in the casting of undesirable shadows because of light 25 flux from the lamp being intercepted by the supporting arms. Again, the lamp of the character above mentioned, or so-called "lyre type" lamp, requires a special construction to adapt it for suspension from the supporting arms, and, in order that the lamp 30 may have a pleasing appearance, it is essential to provide an expensive structure which prevents common use of this type of lamp.

By means of my invention, an arc lamp 35 of a standard form of construction may be employed for a post mounting which insures a substantial support for the lamp and at the same time eliminates the objectionable heavy supporting arms above mentioned.

40 My invention also provides a simple and inexpensive structure by means of which all portions of the lamp are made readily accessible, whereby inspections and replacements may be efficiently and expeditiously 45 made.

For a better understanding of the nature, the scope and the characteristic features of my invention, reference may be had to the following description and the accompanying 50 drawing of which Figure 1 is a view, partially in elevation and partially in section, of an arc lamp embodying a form of my invention, Fig. 2 is a cross sectional view taken on the line II—II of Fig. 1, Fig. 3 is a plan 55 view of the lamp-supporting ring which is

shown in Fig. 1, and Fig. 4 is an enlarged detail view partially in section, of a portion of the device shown in Fig. 1.

A lamp 1 of a standard form of construction engages an annular member 2 which is 60 supported by rigid members 3 that, in turn, are supported by an element 9 seated in the upper portion of a post 4. The supports 3 are positioned exteriorly to an inner globe 5 and are contained in an outer globe 6 which 65 substantially surrounds the inner globe 5. In order to replace the carbons at the end of a trim, it is necessary to have access to them and, to this end the lamp is raised by means of pivoted arms 7 and a sliding sleeve 8 to a 70 position indicated by the broken lines of Fig. 1. When the lamp occupies the latter position, the inner globe 5 may be easily removed, thereby permitting the burned electrodes to be replaced by new electrodes. 75

As shown in Fig. 1, the lamp is disposed upon the ring 2 which sustains the lamp in its normal position by reason of the supporting members 3 being cast in a stationary element 9 of the post 4. The outer globe 6 80 supports none of the weight of the lamp but is designed to engage, at its upper edge, an imperforate ring secured to the base of a condenser 10, and, at its lower edge, a flanged portion 11 of the post 4, the said globe providing a dead air space 12 which is cut off from communication with the outer air and with the chamber of the condenser 10. Inasmuch as the supports 3 are comparatively 85 small in diameter, they intercept only a 90 small portion of the light flux emanating from the lamp and, consequently, the shadows resulting therefrom are not objectionable. To effectively disperse the shadows cast by the members 3, the outer globe 6 95 may be made of a translucent material, such, for example, as opal, which diffuses the light from the arc and practically eliminates the shadows occasioned by interposing the members 3 between the arc and the globe 6. 100

During the operation of the lamp, the sleeve 8 which embraces the stationary element 9 is held in the position shown by suitable means, such as a spring device 13 engaging the lower edge of the sleeve. The 105 arms 7, which are pivoted to the upper portion of the sleeve, are disposed in longitudinally extending recesses 14 formed in opposite sides thereof, as shown in Fig. 2, thus concealing the said arms from view when 110

not in use. When it is required to trim the lamp and therefore to have access to the chamber of the inner globe 5, the sleeve 8 is moved downwardly toward the base (not shown) of the post 4 by disengaging the spring 13 and permitting the sleeve to fall by reason of its weight to the position indicated by the dotted lines of Fig. 1. The pivotally secured arms 7 are withdrawn 10 from their recesses 14 and raised to a position shown by the arm 7^a. As the sleeve 8 is moved upwardly, the upper ends of the arms 7 engage recesses formed in lugs 15, which are firmly attached to the condenser 15 10 of the lamp. Continuing to advance the sleeve 8, the lamp is lifted from its supporting ring 2 and the globe 5 is withdrawn from the outer globe 6. When the sleeve is locked in its initial position by reengagement with the spring 13, the lamp occupies the position shown by the broken lines in which it is accessible for making repairs, inspections and the necessary replacements. The lugs 15 are provided with recesses 25 15^a which receive the ends of the arms 7 when in their raised positions.

After these functions have been performed by the inspector, the lamp is replaced in its operating position by releasing the spring 30 13 and permitting the sleeve 8 to slide downwardly, thereby again engaging the lamp and the ring 2 and disengaging the arms 7 and the lugs 15. Inasmuch as the regulating and feeding mechanisms of the lamp are 35 inclosed in the upper portion of the lamp structure, they may be readily inspected with the lamp in its normal position.

In Fig. 3, the ring 2, which normally supports the lamp, is shown in plan view. The 40 rigid supports 3 are cast into the ring 2 and extend from its lower surface. The upper surface of the ring is finished to provide a substantially air-tight joint between it and the engaged surface of the condenser element 10 of the lamp. In this manner, air currents are substantially precluded from circulating through the dead air space 12 when the arc lamp is in normal position.

While I have disclosed only one embodiment of my invention, it will be understood

that many modifications may be made without departing from the spirit thereof, and I desire that only such limitations shall be imposed as are indicated in the appended claims.

55

I claim as my invention:

1. The combination with an arc lamp, a post member, and a support thereon upon which the arc lamp is normally disposed, of a sleeve slidably engaging the post member, two arms pivotally secured to the sleeve, and means for engaging the arms and the arc lamp adapting the latter to be varied in position in accordance with the position of the sleeve.

60

2. The combination with an arc lamp, a post member, and a support thereon upon which the arc lamp is normally disposed, of a sleeve slidably engaging the post member, two arms pivotally secured to the sleeve, 70 and means for engaging the arms and the arc lamp adapting the latter to be disengaged from the support.

3. The combination with an arc lamp, a post member, and a support thereon upon 75 which the arc lamp is normally disposed, of a sleeve slidably engaging the post member, two arms pivotally secured to the sleeve, means for engaging the arms and the arc lamp adapting the latter to be raised to a 80 predetermined position, and means for maintaining the lamp at the predetermined position.

4. The combination with an arc lamp, an inner and an outer globe therefor, a post 85 member, and a support within the outer globe upon which the arc lamp is normally disposed, of a sleeve slidably engaging the post member, two arms pivotally secured to the sleeve, and means for engaging the arms 90 and the arc lamp adapting the latter to be raised to a position outside the outer globe.

In testimony whereof, I have hereunto subscribed my name this 1st day of Dec. 95 1913.

GEORGE M. LITTLE.
